CLAIM

The ornamental design for a display screen with virtual three-dimensional shoe or display system with virtual three-dimensional shoe, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen with virtual three-dimensional shoe showing my new design in a perspective orientation;

FIG. 2 is another front view thereof, showing a side view of the shoe;

FIG. 3 is another front view thereof, showing an opposite side view of the shoe;

FIG. 4 is another front view thereof, showing a front view of the shoe;

FIG. 5 is another front view thereof, showing a rear view of the shoe;

FIG. 6 is another front view thereof, showing a top view of the shoe;

FIG. 7 is another front view thereof, showing a bottom view of the shoe;

FIG. 8 is a front view of a display system with virtual three-dimensional shoe shown in a perspective orientation, the virtual three-dimensional shoe being the same design as shown in the first embodiment of FIGS. 1-7;

FIG. 9 is another front view thereof, showing a side view of the shoe;

FIG. 10 is another front view thereof, showing an opposite side view of the shoe;

FIG. 11 is another front view thereof, showing a front view of the shoe;

FIG. 12 is another front view thereof, showing a rear view of the shoe;

FIG. 13 is another front view thereof, showing a top view of the shoe; and,

FIG. 14 is another front view thereof, showing a bottom view of the shoe.

The broken lines showing the circular region on the shoe sole and shoe interior form no part of the claimed design. In FIGS. 1-7, the outermost broken line represents a display screen which forms no part of the claimed design. In FIGS. 8-14, the outermost broken line represents a display screen which forms no part of the claimed design.

(Continued)

8-14, the outermost broken line represents a portion of a field of view for a visual display and forms no part of the claimed design.
